UNITED STATES PATENT OFFICE.

ANTON FREDERIKSEN, OF COPENHAGEN, DENMARK.

LOCK.

SPECIFICATION forming part of Letters Patent No. 698,486, dated April 29, 1902.

Application filed October 15, 1900. Serial No. 33,128. (No model.)

To all whom it may concern:

Be it known that I, ANTON FREDERIKSEN, a citizen of Denmark, residing at Copenhagen, Denmark, have invented certain new and useful Improvements in Safety-Locks, of which the following is a full specification.

Referring to the drawings, Figure 1 shows a vertical sectional view, in full size, of the lock with its key, taken on the line 1 1, Fig. 10 4; Fig. 2, a sectional view of the labyrinthic path for a ball, taken on line 2 2, Fig. 1; Fig. 15 3, a front sectional view of the key-bit engaging the said path; Fig. 4, a front view showing the arrangement of the latches, &c., the labyrinth and its casing being removed. Fig. 5 is a section through the knob or key bow on line 5 5 of Fig. 1, somewhat enlarged for the sake of clearness.

Figs. 1 and 2 show the revoluble key-box 20 provided with specially-arranged guideways for the ball 2^a and mounted in the stationary casing 3. The knob 4, forming the bow of the key, having a disk of glass or other transparent material in its front, is provided with 25 guideways for a ball 2, exactly corresponding to those of the key-box, and also with half-circular projections 5 at its periphery corresponding to similar projections 5^a at the periphery of the key-box. These projections 30 are marked with corresponding numbers at, respectively, the outside of the box and on the glass plate of the key-bow.

When the lock is being closed, the ball 2^a will roll in the guideways until it will rest in 35 one of the projections 5^a at the lower side of the key-box. In order to open the door, it will be necessary to set the ball 2 in the bow of the key, so that it will rest in the projection of the bow having the same number as 40 the projection of the key-box in which the ball 2^a rests. Then the key is inserted and turned alternately right and left, as it may be, until the ball 2 of the bow of the key will have arrived at the center of the bow, when 45 the ball 2^a will also have reached the center of the key-box, as shown in Fig. 2.

In the hollow key-shank 6 is placed a pin 7, connected with an arm 9, passing through and slidably movable in the slots 8 of the 50 shank and held in position by a spiral spring 11, bearing against the partition 10.

The socket 12, inclosing the outside project-

ing stop 13, is fastened to the key-box 1, concentric with the center of the same. The end of the hollow key-shank is provided with a 55 slot 15, fit to engage the stop 13, so that by turning the key the key-box will be turned also. By turning the key-box the ball 2^a, rolling in the guideways, will reach the center, Fig. 1, of the key-box and is then pressed 60 by the sliding arm 9 and pin 7. This pin enters through opening 14 in the center of the key-box into the socket 17, which is fastened to the escutcheon 16. The spring 18 is also fastened to the escutcheon and through a fork 65 projecting in the socket 17 will retain the ball 2^a in the key-box until pushed by the pin 17 and will bring it back in position after the lock has been unlocked.

By pushing the ball 2^a into the socket 17 70 the angular-shaped catch 19 engages with its hook 20 in a V-shaped groove of the lock-bolt 21, thus holding this bolt in position and permitting the spring-pressed bolt 22, which is 75 slidably mounted in the door-casing, to enter a slot in the flanged part of the escutcheon, which is flush with the edge of the door-frame, and to bear against the bolt 21 inside of the keeper formed between the partition 23 and the escutcheon-plate 16 and serving as a guide 80 for the two bolts.

When the bolt 21 is released from the hook 20, the bolt 21, actuated by strong springs 24 pressing against the two shoulders of said bolt 21, pushes the bolt 22 back into the door-casing, thereby permitting the door to be 85 opened. The door can be locked again by pushing the pin 26, fastened to the bolt 21 and projecting outside the escutcheon, through a slot 25, which limits the motion of said pin, 90 as shown by Figs. 1 and 4. The hook 20 of the angular catch 19 will then come in engagement with the V-shaped groove of the bolt 21 and permit the bolt 22, as described above, to enter the slot provided at the bent 95 part of the escutcheon.

The lock may be opened without using the key from the inside by shifting the button 29, projecting from the lever 27, which is pivotally fastened to the escutcheon. The pin of said 100 button 29, connecting the button with the lever, passes through the curved slot 28, provided in the escutcheon. By shifting the button 29 the hook 30, forming the other end of

the lever 27, will lift the hook 20 of the catch 19, thereby releasing the bolt 21.

The pin 31 or suitably-arranged balls, rolls, &c., serve to guide the key-box 1.

5 The small opening 14 of comparatively considerable length is the only passage leading to the inside parts of the lock, and it will therefore be impossible to pick the lock, which is made even more difficult by the hook 20, 10 Fig. 1, being tapered at an acute angle.

The spiral ways of the key-box corresponding with the ways of the bow of the key may be made of any suitable shape, and therefore will permit of a great number of combinations 15 for different locks. The socket 12 may be provided with zigzag-formed slots corresponding with the ways of the key-box and the hollow shank of the key provided with a projecting pin entering said slots.

20 Having thus particularly described the nature of my invention and in what manner the same is to be performed, what I desire to claim, and wish to secure by Letters Patent, is—

1. In a safety-lock a revolute key-box 1 25 provided with spiral or labyrinthic guideways for a ball 2^a, a key which is provided with a knob-like bow 4, having guideways and a ball 2 corresponding to those of the key-box, and by engagement with a stop at the key-box 30 turns said box so as to make the ball 2^a roll to the center thereof, and means for pushing the ball inside from said position, a bolt released by said ball when pushed inside.

2. In a safety-lock comprising the revolute key-box with labyrinthic guideways, a ball 2^a rolling therein, a key having hollow shank and knob-like bow with like guideways, and a ball 2 rolling therein, and means whereby both balls may be brought to a central position by turning said key, the combination 35 with said parts of a spring-pressed pin 7 playing in the hollow shank of said key and arranged to enter a small hole in the center of

the key-box, whereby when said pin is pressed forward the ball 2^a in said key-box is pushed 45 back, a spring-ball released by such action, and a door-bolt forced out by said spring-bolt when released.

3. In a safety-lock comprising the revolute key-box with labyrinthic guideway, a ball 2^a rolling therein, a key having similar guideway, and a ball rolling therein, a spring-pressed bolt, and a door-bolt acted upon by said spring-pressed bolt when released, the combination with said parts of an angular 55 lever 19 provided with a lock 20 engaging said spring-bolt to hold it in a retracted position, and means for pushing the ball 2^a in the key-box from a central position against said lever to disengage it and release the spring- 60 bolt.

4. In combination with the spring-bolt 21 and the engaging latch-lever 19 a pin 26 fastened to said bolt and playing in a slot in the escutcheon, whereby said bolt may be moved 65 back to engagement with the latch-lever.

5. In combination with the spring-bolt 21 and engaging latch-lever 19 a manually-operated disengaging-lever 27 pivotally mounted upon the escutcheon and acting at one end 70 upon the hooked end of the latch-lever to disengage it from the spring-bolt and release the latter.

6. The combination with the spring-pressed bolt, the latch-lever by which it is held, the door-bolt, the ball 2^a and its central pocket, of the socket 17, the forked spring 18 and rod or pin 7 movable in the shank of said key.

In testimony whereof I affix my signature 80 in presence of two witnesses.

ANTON FREDERIKSEN.
